Frank J. Bunn
ATTORNEY.

UNITED STATES PATENT OFFICE.

CYRUS HOWARD HAPGOOD, OF NUTLEY, NEW JERSEY, ASSIGNOR TO THE DE LAVAL SEPARATOR COMPANY, OF NEW YORK, N. Y., A CORPORATION OF NEW JERSEY.

PROCESS OF SEPARATING IMPURITIES FROM LIQUIDS.

Application filed August 24, 1921. Serial No. 495,134.

The utilization of centrifugal force to purify liquids by the elimination therefrom of solids or of other liquids of different specific gravity from that of the liquid to be purified, 5 is well known and has been practiced successfully in many arts. Where the separation of two liquids is required and those liquids are immiscible with each other, no special problem arises. Where the liquid to be purified 10 is mixed with solids, these latter may be removed either by means of a centrifugal clarifier or by the introduction of a heavy cushioning liquid into a centrifugal separator. Where a clarifier is used, the solids 15 adhere to the wall of the centrifugal bowl, whose rotation must be arrested at intervals and the solids cleaned out of the bowl by scraping or flushing. In the other process, involving the use of a separator, the heavy 20 cushioning liquid may be present in the original mixture or it may be deliberately added. In either case, if the heavy liquid is of higher specific gravity than the solids, it will carry the solids with it out of the bowl, and even if 25 somewhat lighter than the solids, it may have a sludging action upon the solids that will reduce the frequency with which the bowl must be cleaned.

When two liquids are in solution, it is 30 obvious that centrifugal force is unavailable to separate them. However, in certain cases, the two liquids can be thrown out of solution by subjecting them to a low temperature. Thus, in the separation of waxes or paraffins 35 from cylinder stock, it has been long well known to dilute the cylinder stock with a light petroleum product, such as naphtha and chill to solidify the waxes. The wax can then be removed by settlement. This is a 40 process that was old and well known long before the development and perfection of centrifugal machinery. With modern and more nearly perfected separators, the wax can be removed by utilizing a heavy liquid, 45 such as brine, to carry the wax out of the bowl. This latter process is of questionable value, however, because the problem of separating the wax from the brine, which is theoretically very simple, is practically very difficult, and 50 inasmuch as the wax is a valuable product, no process which fails to secure its economical separation is commercially practicable. Moreover, the above process involves a number of centrifugal operations, as well as con-

stant heating and cooling of the brine, and 55 is therefore complicated and expensive.

It has been found possible, however, with a centrifugal machine of high efficiency, to centrifugally separate the wax from the oil 60 liquid whatever, provided the temperature is not reduced to such a degree as to render the wax non-flowing. However, at the highest permissible temperature that will throw the wax out of solution and maintain it out of 65 solution during the centrifugal operation, the flow of the wax is necessarily relatively sluggish, with the result that although it flows sufficiently freely to discharge from the bowl, it clogs the outflow conduits of the stationary 70 receiving pan, which obstructs the discharge from the pan to the wax receptacle and causes a back flow of the wax into the space between the frame and the bowl. This difficulty, 75 however, I have overcome by subjecting the wax, immediately upon its discharge from the centrifuge, to heat sufficient to change it from a slow flowing semi-solid to a relatively free flowing liquid.

The advantage of the process is that in one 80 centrifugal operation there is a complete separation of the oil from the wax and that the wax is recovered in such condition that its purification presents no technical difficulties.

In order that my invention may be readily 85 carried out by those skilled in the art, I have illustrated a known workable and efficient type of separator together with a special and improved receiving pan which is adapted 90 to be heated and thereby heat the wax discharged thereinto.

In the drawings, Fig. 1 shows the upper 95 part of a centrifugal machine, principally in central section and more or less diagrammatic. Fig. 2 is a plan view of one of the receiving pans, partly broken away.

The cylinder stock is first diluted with about one and one half parts of naphtha. It is then chilled to a temperature of about zero 100 F. In general, the maximum range of the cooling temperature will be from -10° to +10 degrees F. The effect of the cooling is to throw the waxes out of solution and convert them into a viscous liquid or a semi-solid 105 which, however, is sufficiently fluid to discharge from a separator bowl. The stock is then fed into the bowl, where, under the

influence of centrifugal force, the heavier waxes are thrown to the periphery of the bowl, while the lighter oil is displaced inwardly, the two ingredients being separately 5 discharged into two receiving pans. The receiving pan into which the waxes are discharged, or the delivery tubes leading therefrom or both, are steam jacketed, so that immediately upon their discharge from the machine, the temperature of the waxes is raised 10 to so reduce their viscosity that they flow freely out of the spouts into the vessel provided for their reception.

Inasmuch as it is desirable, in practicing 15 my process, to use the most efficient type of separator, I have illustrated the same in detail. It will be understood, however, that the practice of the process is not limited to the use of any particular construction of 20 centrifuge nor to any particular means for heating the waxes upon their emergence from the bowl.

a is the bowl body or shell; *b*, the central feed tube; *c*, conduits leading therefrom to 25 the bottom of the bowl; *d*, the bowl liner the "discs" of which are provided with vertically aligning orifices *e* in vertical alignment with the discharge mouths of the channels *c*; *f*, the top disc; *g*, *h*, wings compelling 30 the heavy materials near the periphery of the bowl to rotate with the bowl.

The heavier waxes are thrown out toward the periphery and escape between the wall of the bowl and the outer edge of the top 35 disc *f*, into the space above the top disc, along which they flow and are discharged from the bowl over the weir *i* at the top of the bowl neck. The lighter oil is displaced inward and flows up inside the neck of the 40 top disc and is discharged over the weir *j* at the top of such neck.

A series of stationary receiving pans *m*, *n* and *o* are provided. The lower pan *m* receives the waxes, the intermediate pan *n* 45 the oil, and the upper pan any overflow from the feed pipe *b*.

The lower pan *m* is provided with integral spouts *k*, which are of limited height but relatively great width. These spouts are 50 steam jacketed, as is the side wall of the pan *m*. The steam jacket is shown at *p*. The waxes discharged from the bowl at *i* immediately contact with this heated wall and are thereby raised in temperature sufficiently 55 to render them more free flowing. As they flow through the spouts *k*, they are surrounded by a heating medium, so that they outflow freely from the contracted ends of the spouts *k*.

60 My invention is also applicable to certain methods of treating wax distillates of petroleum to separate the waxes from the

oil. In the case of wax distillates the congealed waxes are crystalline, instead of amorphous as in the case of cylinder stock, 65 and the permissible range of congealing temperature would be from 20° to 35° F., preferably 25°.

My invention is of particular value in its application to the treatment of cotton seed 70 and other vegetable oils wherein the oil is treated with an alkali to saponify the fatty acids of the oil and the mixture of oil and soap subjected to centrifugal force to separate the soap from the oil. In this process 75 the flow of soap through and out of the receiving pans is so sluggish that it tends to clog the spouts. By my process the objectionable action is entirely overcome.

Having now fully described my invention, what I claim and desire to protect by Letters Patent is—

1. The process of separating from a liquid a substance admixed or emulsified therewith and which, while capable of being separated therefrom by centrifugal force, is relatively non-free-flowing, which comprises subjecting the mixture to centrifugal force to effect the separation of said substance, subjecting the separated substance to the action of a heating medium while maintaining it out of contact therewith, and flowing away the heated substance. 85

2. The process of separating from a liquid a substance soluble therein at a relatively high temperature and insoluble therein at a relatively low temperature, which comprises reducing the solution to a temperature sufficiently low to render said substance insoluble in said liquid, separating said substance from said liquid by centrifugal force, subjecting the separated substance to the action of a heating medium while maintaining it out of contact therewith, and flowing away the heated substance. 95

3. The process of separating from a liquid a substance admixed or emulsified therewith and which, while capable of being separated therefrom by centrifugal force, is relatively non-free-flowing, which comprises 100 subjecting the mixture to centrifugal force, and separately flowing out of the separating chamber the separated constituents, conveying said separated constituents to their ultimate destination and in the course of the 110 travel of one of said separated constituents subjecting it to the action of a heating medium while maintaining it out of contact therewith. 115

In testimony of which invention, I have 120 hereunto set my hand, at Philadelphia, Pa., on this 15th day of August, 1921.

CYRUS HOWARD HAPGOOD.
